[57] CLAIM

The ornamental design for a video tape recorder, as shown and described.

DESCRIPTION

FIG. 1 is a top, front and right side perspective view of a video tape recorder showing our new design;

FIG. 2 is a bottom, rear and right side perspective view thereof, and

FIG. 3 is a front elevational view thereof.

Left side view is identical with right side view.

FIG. 1

FIG. 2

FIG. 3
